(57) **CLAIM**

The ornamental design for a sauce pan side handle, as shown and described.

DESCRIPTION

FIG. 1 is a perspective view from above the front and side of the “sauce pan side handle”, showing my new design;

FIG. 2 is a top plan view thereof;

FIG. 3 is a front elevation thereof;

FIG. 4 is a side elevation view thereof;

FIG. 5 is a bottom plan view thereof;

FIG. 6 is a back elevation view thereof; and,

FIG. 7 is a bottom perspective view thereof.

The broken lines in FIGS. 1-7 are for illustrative purposes only, depicting the rivet holes in the handle, forming no part thereof as claimed.
